[57] ABSTRACT

An exhaust gas recirculation flow control system for

an internal combustion engine having valve means responsive to engine air flow and to recirculated exhaust gas flow and adapted to provide a scheduled flow control signal to an exhaust gas recirculation valve. Pressure responsive means are provided to sense engine air flow and recirculated exhaust gas flow so that these two variables may act singly or collectively through said valve means in order to provide exhaust gas recirculation to the engine's intake manifold which begins smoothly and holds at a relatively constant or scheduled fraction of the engine air flow for maximum effectiveness and minimum loss in vehicle driveability. The exhaust gas recirculation control system inhibits exhaust gas recirculation until engine air flow has increased to some predetermined value and then passes exhaust gas to the intake manifold in a modifiable proportional relationship to the engine air flow. If the exhaust gas recirculation flow tends to become too high or too low a force unbalance created within the valve means closes or opens the exhaust gas recirculation valve an amount necessary to maintain a position such that the exhaust gas recirculation flow is controlled in an increasing relationship to the increasing engine air flow. As engine air flow continues to increase a point is reached in which a force unbalance is again created within the valve means causing the exhaust gas recirculation valve to completely inhibit recirculation of exhaust gas. A temperature responsive member may also be included being operative with the valve means in order to inhibit the flow of exhaust gas at a predetermined low ambient or engine compartment temperature.

FIG. 6
EGR FLOW VS. AIR FLOW

EXHAUST GAS RECIRCULATION FLOW CONTROL SYSTEM

FIELD OF THE INVENTION

This invention relates in general to a device that aids in the reduction of engine exhaust emission pollutants. More specifically, it relates to a device that regulates the amount of exhaust gas being recirculated into an intake manifold of an internal combustion engine such that the exhaust gas recirculation begins smoothly and flows at a relatively constant or scheduled fraction of the engine air flow, the flow being completely inhibited at low ambient temperatures as well as low and high engine air flows in order to maintain acceptable driveability.

BACKGROUND OF THE INVENTION

A major source of atmospheric air pollution is the exhaust from automobile engines. To reduce this problem two general approaches have been taken, namely: (1) exhaust treating devices (e.g. catalytic mufflers, after-burners, etc.) and (2) engine modifications to alter combustion. The latter approach includes devices which advance or retard engine spark timing, temperature responsive speed control devices, and/or "On-Off" type exhaust gas recirculation valves.

The present invention concerns itself with engine modification and in particular an improvement in an exhaust gas recirculation system. Exhaust gas recirculation is required in most passenger cars in order to control oxides of nitrogen per federal and some state exhaust emissions standards. The exhaust gas recirculation (EGR) has been implemented using simple on-off controls. With such controls, the EGR varies as a function of intake manifold vacuum, not necessarily in a desirable manner. To meet the more stringent emission standards for oxides of nitrogen, EGR flow rates equivalent to 15 percent or more of the engine's air flow will have to be used when EGR is a primary means for control of oxides of nitrogen. For maximum effectiveness consistent with acceptable vehicle driveability, the EGR flow should begin smoothly and hold at a relatively constant or scheduled fraction of the engine air flow, and EGR should be inhibited at low ambient or engine temperatures as well as at low and high engine air flows.

The conventional spark timing control systems generally provide good performance and fuel economy, but do not necessarily minimize the output of undesirable exhaust gas elements. Exhaust treating devices on the other hand generally minimize the output of exhaust gas elements, however, at the present state of the art must be used in combination with one of the above mentioned engine modification devices.

Other devices are known such as the venturi vacuum amplifiers which attempt to maintain a degree of proportionality between the amount of EGR and total engine air flow. Although these devices are sensitive to engine air flow there is no "feedback" from the exhaust gas recirculation system enabling adjustments to be made within the system to compensate for changes in the sensed engine variables including the EGR flow rate. Further, the venturi vacuum amplifiers require close manufacturing tolerances in order to maintain proper control.

SUMMARY OF THE INVENTION

It is therefore the primary object of this invention to disclose a closed loop exhaust gas recirculation control system which achieves optimum control of exhaust gas recirculation for maximum effectiveness and minimum loss in vehicle driveability. Pursuant to this object an EGR flow control system is disclosed herein, characterized by an engine air flow responsive means operative to provide a pressure signal related to engine air flow, an exhaust gas flow responsive means operative to provide a pressure signal related to exhaust gas flow, and a pilot valve member which through a plurality of diaphragms secured thereto sums these pressure signals in order to regulate an exhaust gas recirculation valve on a proportional basis. The pilot valve is biased so as to inhibit EGR flow at low engine air flow, and a cutoff valve operative with the pilot valve is included to inhibit EGR flow at high engine air flow. A temperature responsive member may be included adapted to react with the cutoff valve in order to inhibit EGR flow at a predetermined low ambient temperature. Thus, a closed loop EGR flow control system results having means responsive to internal combustion engine variables including exhaust flow and engine air flow.

It is another object of this invention to provide an EGR flow control system which reduces the amount of exhaust gas emissions of undesirable elements while simultaneously maintaining acceptable vehicle driveability.

Another object of this invention is to provide an exhaust gas recirculation flow control system wherein the amount of exhaust gas recirculated to the engine intake manifold is regulated by a pilot valve which is responsive to engine air flow, exhaust gas flow, manifold pressure, and/or adverse temperature conditions.

It is still a further object of the present invention to disclose an exhaust gas recirculation system which is designed so that its mechanical features may be easily modified or changed to produce a scheduled relationship between EGR flow and engine air flow which departs from proportionality.

Yet another object of this invention is to provide an economical exhaust gas recirculation flow control system which may be utilized in combination with presently available exhaust gas recirculation valves.

The above and other objects and features of the invention will become apparent from the following detailed description taken in conjunction with the accompanying drawings and claims which form a part of this specification.

BRIEF DESCRIPTION OF THE DRAWINGS

FIG. 1 is a cross sectional view of the control assembly of the preferred embodiment of this invention.

FIG. 2 is a cross sectional view of the preferred embodiment of the exhaust gas flow sensing means and its interrelationship with the standard EGR type valve.

FIG. 3 is a schematic view of a carburetor normally associated with an internal combustion engine and illustrating the engine air flow sensing means.

FIG. 4 is a partial cross sectional view of the pilot valve member shown in FIG. 1 and illustrating an alternative embodiment of the invention which incorporates a temperature responsive member.

FIG. 5 is a block diagram of the preferred embodiment of my exhaust gas recirculation flow control system.

FIG. 6 graphically illustrates the test results of my invention as applied to an existing internal combustion engine.

FIG. 7 is an alternative embodiment of the exhaust gas flow sensing means.

DETAILED DESCRIPTION OF THE DRAWINGS

The exhaust gas recirculation flow control system according to the invention is comprised of the engine air flow sensing means 40 shown in FIG. 3, the exhaust gas flow sensing means 30 shown in FIG. 2, and the control assembly 20 including the pilot valve member and its related structure shown in FIG. 1 which controls the exhaust gas recirculation (EGR) valve 10 shown in FIG. 2. An example of a temperature responsive member 50 which may be used in combination with the inventive system is shown in FIG. 4. The interrelationship of the various system components is illustrated by the block diagram shown in FIG. 5.

Referring to FIG. 3 a carburetor 41 is shown as being of the down draft type and having the usual air-fuel induction passage 45 with an atmospheric air inlet 44 at one end and connected to the engine intake manifold 47 at the opposite end. Passage 45 contains the usual fixed area venturi 42 and a throttle valve 46. The latter is rotatably mounted on a part of the carburetor body across passage 45 in a manner to control the flow of air-fuel mixture into the intake manifold. Fuel would be inducted in the usual manner from a nozzle, not shown, projecting into or adjacent venturi 42, in a known manner.

Throttle valve 46 is shown in its engine idle speed position essentially closing induction passage 45 and is rotatable to a nearly vertical position essentially unblocking passage 45. A port 49 is provided in the throat of venturi 42 which in combination with the venturi 42 and a passage 48 mounted adjacent to port 49 comprise the engine air flow sensing means. It is to be understood that the pressure or vacuum level at venturi port 49 is a function of the total air flow passing through venturi 42. That is, engine air flow is regulated by the relative position of throttle valve 46. As the throttle valve opens air flow increases which in turn causes the air pressure at port 49 to decrease with respect to atmospheric pressure, or pressure at an upstream stagnation point which is not shown. The "vacuum" which is created at venturi port 49 may be termed a pressure signal which for purposes of discussion we will label as S_1 . Pressure signal S_1 is communicated to the pilot valve housing 21 shown in FIG. 1 through passage member 48. The cross sectional area of the throat of the venturi 42 is designated as A_1 . The cross sectional area A_1 is a design parameter which must be known since the disclosed system regulates EGR flow on either a scheduled or proportional relationship with the air flow which passes through this orifice.

A spark port 43 may be provided at a point just above the idle position of throttle valve 46, to be traversed by the throttle valve during its opening or part throttle movement. The vacuum level at spark port 43 will change as a function of the rotative position of the throttle valve, the spark port 43 reflecting essentially atmospheric pressure in the air inlet 44 upon closure of the throttle valve. The vacuum level sensed at port 43

may be communicated through passage member 115' to the vacuum reservoir 122 shown in FIG. 1. With this modification incorporated into the system exhaust gas recirculation would be inhibited at small throttle openings as well as at low engine air flow for reasons which will become more apparent from the following description.

One skilled in the art will appreciate that although the engine air flow sensing means 40 is described as relating to a carburetor 41, element 40 can also be referred to more generally as a throttle body since the disclosed system could be used in combination with any fuel metering system which senses air flow or in which an air flow sensor has been added.

Referring to FIG. 2 the exhaust flow responsive means 30 is shown. A housing 31 has a passage 32 formed therein to which is connected a pipe 33 from the exhaust manifold and a pipe 34 connected to the intake manifold. Disposed within the passage 32 and fixedly secured thereto is an exhaust venturi 35. An opening 35' having a cross sectional area A_2 is provided in the throat of venturi 35. Housing 31 has a passage 36 disposed adjacent the opening 35' and a passage 37 located upstream of the venturi 35. A valve seat 38 having a cross sectional area A_3 is formed downstream of venturi 35 in the passageway 32. Passageway 32 exhausts through an orifice 39 having a cross sectional area A_4 downstream of the valve seat 38. Arrow E shows the direction of recirculated exhaust gas flow

An EGR valve 10 which is of standard design is fixedly secured to the housing 31 by conventional means such as bolting. The EGR valve is of the spring biased diaphragm type having a rod 12 fixedly secured to the diaphragm 13. Diaphragm 13 divides the housing

11 of the EGR valve into two separate chambers 14 and 15, chamber 14 being exposed to ambient air through an opening (not shown) and chamber 15 being connected to pilot valve 21 (shown in FIG. 1) through a passage 16. Valve 18 which is fixedly secured or integrally formed on the rod 12 is biased against the valve seat 38 of housing 31 by the spring 17 which has a predetermined spring force F_1 . It is to be understood that as the pressure varies across the diaphragm 13 the rod and therefore the valve 18 will move toward or away from the valve seat 38 thereby controlling the amount of exhaust gas passing through the passage 32.

One skilled in the art will appreciate that when a venturi is used as a flow sensing element, the largest pressure differential is established by measuring the upstream pressure using a stagnation tap i.e. 37, and measuring the pressure at the throat of the venturi i.e. 35'. Passage member 37 which has an opening 37' senses the exhaust gas pressure S_2 in the passage 32 and communicates this pressure signal to the pilot valve housing 21, and passage member 36 communicates the pressure S_3 of the exhaust gas at the opening 35' to the valve housing 21. The differential between pressure signals S_2 and S_3 increases with the flow rate of exhaust gas passing through the venturi 35 in a manner like the differential between atmospheric pressure and S_1 increases with the flow rate of engine air passing through carburetor venturi 42.

Although not specifically shown, the EGR venturi 35 could be located downstream of the EGR valve 18. This approach is less desirable however, since the manifold pressure differential (which would greatly influence S_2 and S_3) is much greater than the exhaust pres-

sure sensed upstream of the EGR valve 18 thus making the control function of the pilot valve shown in FIG. 1 more difficult.

Referring to FIG. 1 the control assembly 20 of the exhaust gas recirculation flow control system is shown. Pilot valve housing 21 is of laminated construction with section 21a and 21b retaining a diaphragm 60, sections 21b and 21c retaining diaphragms 70 and 170 and sections 21c and 21d retaining a diaphragm 80 therebetween. These four laminated sections form a cavity 22 which because of the diaphragms 60, 70 and 80 is divided into separate chambers 22a, 22b, 22c, and 22d. Disposed within cavity 22 and fixedly secured to the diaphragm 60, 70 and 80 is a pilot valve member 23. The portions of diaphragms 60, 70 and 80 which are included within the cavity 22 have "effective" cross sectional areas A_1 , A_2 and A_3 respectively. The "effective" area is a function of both the outside diameter of the diaphragms and the diameter of the pressure distribution washers.

Pressure signal S_1 is communicated to chamber 22a by means of a passage 21a' interconnecting cavity 22a with the hose 37. Pressure signal S_2 is communicated to cavity 22b through a passage 21b' which interconnects cavity 22b to the hose 38. Cavity 22c is subject to a pressure signal S_3 which is communicated to cavity 22c by means of a passage 21c' formed in laminated section 21c. Cavity 22d is subject to atmospheric pressure communicated to cavity 22d through passage 21d' formed in laminated section 21d. Cavity 22d is also connected through passage 91 to another cavity 90 formed in laminated section 21d. A valve seat 92 is formed in passage 91 adjacent cavity 90, and another valve seat 93 is formed in a passage 95 which leads into cavity 90 diametrical to valve seat 92. Valve seat 93 has a cross sectional area A_4 . A passage 94 formed in section 21d interconnects cavity 90 to passage 16.

Another laminated section 21e of the pilot valve housing 21 is fixedly secured to laminated section 21d such that a passage 21e' formed therein mates with passage 95. A flow restriction member 110 having a passage 111 therethrough is threadedly received in the passage 21e'. Passage 21e' opens into a reservoir 122 formed within section 21e. Intake manifold pressure P_m is communicated from the intake manifold 47 to the reservoir 122 by means of a hose 115. A check valve 124 of standard design is disposed about the openings 123 of reservoir 122 in order to insure an adequate vacuum source regardless of variation in engine manifold vacuum.

Pilot valve 23 which more functionally may be referred to as a summing means is comprised essentially of three main parts, two stem portions 24 and 25 and a piston member 26. Stem portion 24 is fixedly secured to diaphragm 60 by a plurality of discs 61 and a screw 62 in a known manner. Stem portion 25 is threadably received within stem portion 24 compressively securing diaphragm 70 therebetween. Stem portion 25 has a piston chamber 71 formed therein for receiving piston member 26. Piston 26 has a flange 26' to which is mounted a plurality of discs 81 and a nut 82 arranged to compressively secure diaphragm 80 to the piston 26. The top most extension of piston 26 (referring to FIG. 1) is slidably disposed within chamber 71 of valve stem member 25. A spring 87 having a spring force F_1 is disposed about stem portion 25 biasing piston 26 away from its sliding connection with stem 25. The lower

most extension of piston 26 has a valve 27 fixedly secured thereto such as by riveting. Of course valve 27 may be integrally formed with the piston 26. Valve 27 is adapted so as to seat against either valve seat 92 or valve seat 93 as the piston 26 translates therebetween. A pressure signal S_4 which is communicated from cavity 90 to the EGR valve 10 is a function of the relative position of piston 26 and may be magnitude equal to atmospheric or manifold pressure or in between. S_4 may be outside these limits under special circumstances to be described.

A cut-off valve 223 is disposed within a cavity 222 formed by laminated sections 21b, 21c and 21d. Cavity 22 is divided into four chambers, chambers 222a and 222b which are divided by a diaphragm 170, chamber 222c and chamber 222d, chamber 222b and 222c being interconnected by a passage 221c'. Cut-off valve 223 has a main stem portion 224 which is riveted to a plurality of discs 171 compressively securing stem 224 to the diaphragm 170. The portion of diaphragm 170 included within the chamber 222 has an effective cross sectional area A_{11} . A valve member 225 is fixedly secured to the lower most extension of the valve stem 224 in a conventional manner and is adapted to move toward and away from a valve seat 226 formed at the lower most extremity of passage 221c'. A spring reaction member 228 is threaded within the chamber 222d of the laminated section 21d confining a spring 227 between the valve 225 and the reaction member 228. Spring 227 has a spring force F_2 and is adapted to bias valve head 225 into contact with the valve seat 226. Chamber 222a is exposed to atmospheric pressure through the passage 221b formed in laminated section 21b. Chamber 222b is exposed to the pressure signal S_1 by means of a channel 48' formed in laminated section 21c which is adapted to receive the hose 48. Chambers 222c and 222d are exposed to atmospheric pressure through an opening 229 in the bottom of laminated section 21d. A filter 230 is fixedly confined within the opening 229 in order to insure the purity of all air entering the cavity 222d and the passage 21d'. Cavity 22c and the passage 221c' are interconnected by passage 21c'.

Referring to FIG. 4 an alternative embodiment of invention incorporating the temperature responsive member 52 is shown. The portions of the control assembly 20 which are the same as that shown in FIG. 1 carry the same reference numerals in FIG. 4. The rivet 172 which secures the discs 171 to the diaphragm 170 has an extended portion 172'. A bimetallic strip 52 is fixedly secured to the laminated section 21b' by a screw 54 or other conventional means. The bimetallic strip 52 is in contactive engagement with the extended portion 172' of the rivet 172. It is to be understood that the bimetal strip 52 senses the temperature in the vicinity of the control assembly 20 i.e. the engine compartment temperature, and in response to a predetermined low temperature will react against the cut-off valve 223 thus terminating the communication of pressure signal S_4 to the chamber 22c as will be described below. Of course, other temperature responsive means could also be incorporated in this invention so that the control assembly 20 would also be responsive to other temperature variables, as for example, the temperature of the engine coolant.

Referring to FIG. 7 an alternative embodiment of the exhaust flow sensing means 30' is shown. The portions

of the exhaust flow sensing means 30' which are identical in structure to that shown in FIG. 2 are designated by the same reference numerals. And the new structure having equivalent functions as the parts shown in FIG. 2 are preceded by the numeral 1. An exhaust flow sensing member 135 having an orifice 135' therethrough is fixedly secured within the passage 32. The flow sensing member 135 serves the same purpose as the venturi 35 shown in FIG. 2 and the pressure S_3 which is sensed at the throat 35' is the same as the pressure adjacent the orifice 135'. By making the cross sectional area A_3 equal to the cross sectional area A_1 of the orifice 39 shown in FIG. 2, the function of orifice 39 is performed simultaneously with the function of orifice 135'. That is, the exhaust flow sensing member 135 serves the dual function of limiting EGR flow as well as sensing EGR flow.

OPERATION

Operation of the exhaust gas recirculation flow control system will be described in sequence as the engine air flow increases from some very low level. The carburetor venturi pressure S_1 is communicated from the carburetor through passage 48 to the underside of diaphragm 170. The pressure signal S_1 decreases as the engine air flow increases through the carburetor and S_1 is always less than the atmospheric pressure P_a which is being felt on the top side of diaphragm 170. The spring force F_2 is strong enough to bias the cut-off valve 223 upwardly at low engine air flows, so that the pressure S_2 is equal to S_1 .

When the engine air flow has increased to some predetermined value, the pressure differential P_a minus S_2 , felt across diaphragm 80 will be sufficient to overcome spring force F_2 of spring 87. This will cause piston 26 of the pilot valve 23 to lift upwardly tending to close valve 27 against valve seat 92, thus making S_2 more a function of intake manifold pressure P_m than atmospheric pressure P_a . The pressure signal S_2 is communicated to chamber 15 of the EGR valve 10, causing diaphragm 13 to react against the spring force F_1 of spring 17 thereby opening valve 18 causing exhaust gas to flow through venturi 35. The EGR flow through venturi 35 produces a differential pressure S_3 minus S_2 . Since these two pressure signals are communicated to both sides of diaphragm 60 of the pilot valve 23, and since S_3 is less than S_2 , a downward force is developed on the diaphragm 60. An additional component of downward force is caused by the pressure differential S_3 less S_2 , acting on the diaphragm 70. This causes a further compression of the spring 87, and the pilot valve assembly 23 through the three diaphragms 60, 70 and 80 acts as though rigidly attached to a common stem. If the EGR flow becomes excessive, the pressure differential S_2 minus S_3 will cause a force unbalance on diaphragm 60 thereby tending to force valve 27 into contact with valve seat 93 which in turn admits atmospheric pressure P_a to the EGR valve chamber 15; this in turn causes valve 18 to move toward valve seat 38 thereby cutting EGR flow. The forces reacting on diaphragm 13 of the EGR valve 10 therefore, tend either to adjust the relative open or closed position of valve 18.

As the engine air flow continues to increase and S_2 continues to decrease valve 27 continues to move upwardly. Simultaneously, the balance of forces on the pilot valve 23 demand a corresponding increase in the pressure differential S_2 minus S_3 , since the further

opening of valve 18 causes an increase in EGR flow. Thus, the pilot valve will maintain a position to control the EGR flow in an increasing relationship to the increasing engine air flow. If the effective area A_4 of diaphragm 60 is equal to the effective area A_3 of the diaphragm 80 and if also the areas A_1 and A_2 are sufficiently small, the EGR flow will be in direct proportion to the engine air flow.

Alternatively, the cross sectional areas A_1 and A_2 of diaphragm 70 and passage 95 respectively, or an additional spring (not shown) can be used with the effect of exhaust back pressure and intake manifold pressure, to produce a scheduled relationship between the EGR flow and the engine air flow which depart from proportionality. The system amounts to a closed loop control having its set point varied by means of other sensed variables. It is to be understood that the control assembly 20 is a means for summing the pressure signals S_1 and S_3 so that the amount of recirculated exhaust gas entering the intake manifold varies in a modifiable proportional relationship to engine air flow.

When the EGR flow becomes limited by the effect of orifice 39, the pressure differential S_1 minus S_3 can no longer adjust to satisfy the force balance on the pilot valve 23. The pilot valve will then cause valve 27 to be seated against valve seat 92 causing S_2 to equal P_a . Under these conditions reservoir 122 can be effective to maintain a vacuum on the EGR valve 10 that is higher than the engine manifold vacuum. This permits designing the EGR valve to operate at substantial vacuum levels while still having the capability of delivering EGR flow at very low manifold vacuums. That is, the combination of the reservoir 122 and the check valve 124 maintain an adequate vacuum source regardless of variations in engine manifold vacuum and regardless of whether the reservoir is controlled by spark port pressure or by manifold pressure. Although orifice 39 with cross sectional area A_1 is not essential, unless such an orifice is used, the flow of EGR would continue to increase with increasing air flow until the point of cut-off is reached.

As the engine air flow continues to increase, the EGR flow will increase only slightly owing to the increase in exhaust back pressure. At a point determined by the spring force F_3 of the spring 227 the pressure drop across diaphragm 170 will be large enough to close cut-off valve 223. That is, valve member 235 which is secured to the valve stem 224 of the cut-off valve 223 will seat against the valve seat 236 formed at the upper end of passage 221c' and valve 225 will be released from valve seat 226 allowing atmospheric pressure to be communicated through passage 221c' and passage 21c' to chamber 22c. Since S_2 will then equal P_a , the force balance on diaphragm 80 shifts the position of valve 27 into contact with valve seat 93 so that S_2 becomes equal to P_a thereby closing EGR valve 10.

By modifying and changing the various design parameters shown herein and for example, by using the spark port pressure of the carburetor 40 instead of the intake manifold pressure P_m in the reservoir 122, different criteria for affecting "cut-in" and "cut-off" of EGR flow can be accomplished.

As was described above the temperature responsive element 52 as shown in FIG. 4 can be caused to react on the stem of cut-off valve 223 making the system responsive to low and/or high ambient or engine compartment temperature in order to inhibit the EGR flow.

when either of these conditions may exist. That is, as the engine compartment temperature decreases a predetermined temperature is eventually reached which will cause the bimetallic strip to bend downwardly in the direction of arrow T shown in FIG. 4 forcing the valve stem 223 downwardly cutting off the pressure signal S₁. This means that atmospheric pressure is communicated to chamber 22c forcing stem 26 downwardly which in turn admits atmospheric pressure to the EGR valve 10.

Flow restriction member 110 shown in FIG. 1 serves the purpose of limiting the flow of air into the intake manifold so as to avoid creating air fuel ratio errors which might occur if any large amount of fresh air were allowed to bypass the carburetor into the intake manifold. Note, that any time valve 27 is between its two valve seats, there is a continuous flow of fresh air through passage 21d', channel 91, and cavity 122, etc. into the intake manifold. Means to prevent this air flow from having the noted adverse effect is important to the overall system.

Referring to FIG. 6 actual test results are graphically illustrated. Lines A and C represent plots of an EGR system designed for EGR flows of exactly 10 and 30 percent of the engine air flow respectively. Line B is a plot of the disclosed system wherein intake manifold vacuum varied substantially between 6 and 14 inches of mercury. It is important to note that all the objects of the invention are accomplished, since EGR is inhibited at low and at high engine air flows, and EGR flow begins smoothly and flows at a relatively constant or scheduled fraction of the engine air flow.

While only one preferred embodiment and two forms of alternative embodiments of the inventive system have been disclosed, it will be apparent to those skilled in the art that changes may be made to the invention as set forth in the appended claims and in some instances certain features of the invention may be used to advantage without corresponding use of other features. For example, it was pointed out that control of the pilot valve 23 can be easily modified by changing certain of the design parameters, and certain of the pressure sensitive cavities contained in the housing 21 may sense pressures other than those specifically described. Also, on a qualitative basis pilot valve 23 could control the EGR flow directly. However, since the venturi vacuum signals are relatively low and since the EGR valve must have significant area, this approach would require very large diaphragm and would thus be impractical. Accordingly, it is intended that the illustrative and descriptive materials herein be used to illustrate the principles of the invention and not to limit the scope thereof.

I claim:

1. In an exhaust gas recirculation flow control system for an internal combustion engine having valve means disposed within the recirculated exhaust gas passage, the improvement comprising:

means for generating a first differential pressure responsive to engine air flow;

means for generating a second differential pressure responsive to recirculated exhaust gas flow; and

means for summing said first and second differential pressures and operative to regulate the relative opening and closing of said valve means so that the volume of exhaust gas being recirculated varies in a proportional relationship to engine air flow.

2. The combination as claimed in claim 1 and including further means for terminating the communication of said first pressure signal to said summation means when engine air flow has increased to a predetermined value.

3. The combination as claimed in claim 1 and including further means for terminating the communication of said first pressure signal to said summation means when the engine compartment temperature reaches a predetermined value.

4. The combination as claimed in claim 1 including further biasing means operative with said summation means for maintaining said valve means in a closed position until engine air flow reaches a predetermined minimum value.

5. In combination with an internal combustion engine having passage means for recirculating exhaust gas to the intake manifold an exhaust gas recirculation flow control system comprising:

engine air flow sensing means responsive to a predetermined range of volumetric air passing therethrough and operative to provide a first pressure signal related to said air flow;

first pressure sensitive means responsive to said first pressure signal;

exhaust flow sensing means responsive to a predetermined range of volumetric exhaust gas passing therethrough and operative to provide a second pressure signal related to exhaust gas flow;

second pressure sensitive means responsive to said second pressure signal;

first valve means operatively disposed in the exhaust gas passage means so as to regulate the amount of exhaust gas entering the engine's intake manifold, and

second valve means operatively interconnecting said first and second pressure sensitive means so that said first and second pressure signals act to control the relative position of said first valve means.

6. The combination as claimed in claim 5 wherein said second valve means is operative to move between a first port and a second port, said first port being exposed to ambient air and said second port being exposed to intake manifold vacuum.

7. The combination as claimed in claim 5 including further third valve means operatively disposed between said engine air flow sensing means and said second valve means, said third valve means being operative to move between a first position wherein said first pressure signal is communicated to said second valve means and second position wherein ambient air is communicated to said second valve means.

8. The combination as claimed in claim 7 including further a temperature responsive member operatively connected to said third valve means to control its relative position under predetermined temperature conditions.

9. The combination as claimed in claim 7 wherein said third valve means includes a third pressure sensitive means, said pressure sensitive means being exposed to said first pressure signal on side thereof and to ambient air on the other side thereof.

10. The combination as claimed in claim 5 including further at least one carburetor for providing an air fuel mixture to the engine, said carburetor having at least one venturi therein.

11. The combination as claimed in claim 10 wherein the engine air flow sensing means includes an opening in the throat of said carburetor venturi, and passage means for communicating the pressure at said opening to said first pressure sensitive means.

12. The combination as claimed in claim 5 wherein said exhaust flow sensing means includes a venturi disposed in the exhaust gas passage means, said venturi having an opening in the throat thereof; and passage means operative to communicate the pressure at said opening to said second pressure sensitive means.

13. The combination as claimed in claim 5 wherein said exhaust flow sensing means includes a flow sensing element disposed within the exhaust gas passage means, said flow sensing element having an opening therethrough; and

passage means operative to communicate the pressure at said opening to said second pressure sensitive means.

14. In combination with an internal combustion engine having exhaust gas passage means for recirculating exhaust gas to the engine intake manifold, an exhaust gas recirculation flow control system comprising:

engine air flow responsive means operative to provide a first differential pressure related to engine air flow;

exhaust gas flow responsive means operative to provide a second differential pressure related to exhaust gas flow; and

means for summing said first and second differential pressures and operative to regulate the amount of exhaust gas being recirculated to the engine's intake manifold so that the volume of exhaust gas being recirculated varies in a modifiable proportional relationship to engine air flow.

15. The combination as claimed in claim 14 wherein said summing means includes a piston member which moves between a first port and a second port, said first port being exposed to ambient air pressure and said second port being exposed to intake manifold vacuum.

16. The combination as claimed in claim 14 wherein said summing means includes a piston member which moves between a first port and a second port, said first port being exposed to ambient air pressure, and said second port being exposed to carburetor spark port vacuum.

17. The combination as claimed in claim 14 including further passage means for communicating said first pressure signal to said summing means; and

valve means operatively disposed in said passage means such that it controls the communication of said first pressure signal to said summing means.

18. The combination as claimed in claim 17 including further temperature responsive means operatively connected to said valve means such that said first pressure signal is prevented from reaching said summing means when a predetermined temperature condition is

reached.

19. In an exhaust gas recirculation flow control system for an internal combustion engine having valve means disposed within the recirculated exhaust gas passage, the improvement comprising:

means for generating a first pressure signal responsive to engine air flow;

means for generating a second pressure signal responsive to recirculated exhaust gas flow;

means for summing said first and second pressure signals and operative to regulate the relative opening and closing of said valve means so that the volume of exhaust gas being recirculated varies in a proportional relationship to engine air flow; and means for terminating the communication of said first pressure signal to said summation means when the engine compartment temperature reaches a predetermined value.

20. In combination with an internal combustion engine having exhaust gas passage means for recirculating exhaust gas to the engine intake manifold, an exhaust gas recirculation flow control system comprising:

engine air flow responsive means operative to provide a first pressure signal related to engine air flow;

exhaust gas flow responsive means operative to provide a second pressure signal related to exhaust gas flow; and

means for summing said first and second pressure signals and operative to regulate the amount of exhaust gas being recirculated to the engine's intake manifold so that the volume of exhaust gas being recirculated varies in a modifiable proportional relationship to engine air flow, said summing means includes a piston member which moves between a first port and a second port, said first port being exposed to ambient air pressure and said second port being exposed to intake manifold vacuum.

21. In combination with an internal combustion engine having exhaust gas passage means for recirculating exhaust gas to the engine intake manifold, an exhaust gas recirculation flow control system comprising:

engine air flow responsive means operative to provide a first pressure signal related to engine air flow;

exhaust gas flow responsive means operative to provide a second pressure signal related to exhaust gas flow; and

means for summing said first and second pressure signals and operative to regulate the amount of exhaust gas being recirculated to the engine's intake manifold so that the volume of exhaust gas being recirculated varies in a modifiable proportional relationship to engine air flow, said summing means includes a piston member which moves between a first port and a second port, said first port being exposed to ambient air pressure, and said second port being exposed to carburetor spark port vacuum.
